CLAIM

The ornamental design for a chin protector, as shown and described.

DESCRIPTION

FIG. 1 is an upper perspective view of a chin protector showing my new design.

FIG. 2 is a lower perspective view of a chin protector showing my new design.

FIG. 3 is a front view of a chin protector showing my new design.

FIG. 4 is a right side view of a chin protector showing my new design.

FIG. 5 is a left side view of a chin protector showing my new design.

FIG. 6 is a rear view of a chin protector showing my new design.

FIG. 7 is a top view of a chin protector showing my new design; and,

FIG. 8 is a bottom view of a chin protector showing my new design.

Any shading and cross-hatching are not features of the design but are utilized to illustrate the surface contours of the chin protector design in the drawings.

The "JACKAL JAW" lettering and icon shown in broken lines is a registered trademark of Jackal Jaw, LLC.

The broken lines illustrate portions of the article that form no part of claimed design.

1 Claim, 7 Drawing Sheets
